Primary Examiner — Messina L Smith

(57) **CLAIM**

The ornamental design for a griddle, as shown and described.

DESCRIPTION

The patent or application file contains at least one drawing executed in color. Copies of this patent or patent application publication with color drawing(s) will be provided by the Office upon request and payment of the necessary fee.

FIG. 1.1 is a front perspective view of a griddle showing the new design;

FIG. 1.2 is a front view thereof;

FIG. 1.3 is rear view thereof;

FIG. 1.4 is a top view thereof;

FIG. 1.5 is a bottom view thereof;

FIG. 1.6 is a right side view thereof;

FIG. 1.7 is a left side view thereof;

FIG. 1.8 is a rear perspective view of the griddle, shown in an alternate configuration;

FIG. 1.9 is a rear perspective view of the griddle; and

FIG. 1.10 is a top, left, front perspective view therefore.

In the drawings the portion of the article shown in the color red in Figure 1.5 form no part of the claimed design.
